United States Patent Office.

BENJAMIN W. HOPPER, OF ASTORIA, NEW YORK.

Letters Patent No. 91,019, dated June 8, 1869.

IMPROVED BELL-LEVER BOX.

The Schedule referred to in these Letters Patent and making part of the same.

To all whom it may concern:

Be it known that I, BENJAMIN W. HOPPER, of Astoria, Queens county, in the State of New York, have invented a new and improved Bell-Lever Box; and I do hereby declare that the following is a full, clear, and exact description thereof, which will enable others skilled in the art to make and use the same, reference being had to the accompanying drawings.

Figure 1 is a front view of my improved bell-lever box, the cap-nut being removed and part of the socket-plate being broken away.

Figure 2 is a detail sectional view of the same, taken through the line $x x$, fig. 1.

Similar letters of reference indicate corresponding parts.

My invention has for its object to improve the construction of bell-lever boxes, so as to make them less liable to get out of order, more easily adjusted, more conveniently attached to the wall, and which may be readily adjusted for a right or left lever; and

It consists in the construction of the box, as herein-after more fully described.

A represents the bell-lever box, which is cast with lugs a' , for convenience in attaching it to its support.

The box A is made entirely close, except the openings, to receive the spout B, through which the bell-wire passes, and the pipe C, through which a wire may be passed leading up to the upper rooms of the house, when required.

The wire-spout B is detachable, so that it may be attached with equal facility, whether the box be adjusted for a right or left movement of the lever.

By making the box A close, it is impossible for particles of the plastering to drop into the spout B and choke it up, impeding the action of the bell-wire.

To enable the pipe C to be conveniently attached, whether the box A be adjusted for a right or left-hand movement of the lever, two holes are formed in the

box A for its reception, one upon each side of the hole for the spout B, as shown in fig. 1.

D is the socket or seat, to which the lever E is pivoted, and which is secured in place in the box A by screws, screwing into the support to which the box A is secured, so that no blocking will be required.

In the case of wooden houses, the socket or seat D is screwed to the same timber to which the box A is secured.

In the case of brick houses, the box A is secured, by screws or rivets, to a plate, F, extending beyond the sides of the box A so far that nails may be driven through said plate into the seams between the bricks.

In this case, a metal or other block or back, G, should be securely attached to the rear side of the plate F, and entering a recess formed in the brick-work to receive it, into which enter the screws, by which the lever, socket, or seat D is secured in place.

This construction enables the apparatus to be attached to a wooden or brick house with equal facility.

H is the cap-nut, which is screwed upon the outer end of the lever-pivot in the ordinary manner.

Having thus described my invention, What I claim, and desire to secure by Letters Patent, is—

1. The close bell-lever box A, constructed with sockets, to receive the spout B and pipe C, either or both, substantially as herein shown and described, and for the purpose set forth.

2. The combination of the plate F and block or back G with the box A, and with the socket or seat D, substantially as herein shown and described, and for the purpose set forth.

The above specification of my invention signed by me, this 31st day of March, 1869.
